ANODE PACKAGE

Robert H. Long, Brooklyn Village, Ohio, assignor
to The Harshaw Chemical Company, Cleveland,
Ohio, a corporation of Ohio

Application August 18, 1949, Serial No. 110,919

2 Claims. (Cl. 206—46)

1

This invention relates to a special package adapted to facilitate the shipping and handling of electrodeposition anodes.

I am aware that prior to my invention it has been proposed to attach skids to packing boxes to enable them to be handled more conveniently. I am aware, also, that platforms provided with feet for the purpose of spacing them from a supporting floor and straps to hold a load thereon have been known for a long time. Accordingly, I do not claim broadly a package with skids attached but only the improved special anode package having skids associated with the anode bars in a simple and advantageous manner as will now be specifically described in connection with the accompanying drawings wherein Fig. 1 is a side elevation of a package in accordance with the invention; Fig. 2 is a plan view of the package shown in Fig. 1 and Fig. 3 is an end view thereof looking from left to right in Fig. 1.

In the electroplating industry, metal is supplied to the electroplating solution most frequently in the form of elongated bars which have one end provided with a supporting hook for hanging the anode on a bus bar, or it may be drilled and tapped so that the electroplater himself attached the hook, using the same one repeatedly, and purchases the anode bar in lengths suitable to his need and having one end drilled and tapped with a standard sized opening and thread to receive the hook which he has on hand. If the hook is not reused, it may anyway be sold separately and attached to the anode bar by the electroplater. The present invention has to do with the handling and packaging of anodes of this sort, that is, bars of lengths usually in the order of 24 to 60 inches and which ordinarily are of approximately elliptical cross-section. These bars may be of a size such that they weigh about a pound per inch of length, or of other size as desired. It can be seen that if a package should consist of 20 bars each 40 inches long and weighing one pound per inch of length, the weight of such a package would be about 800 pounds plus the packaging material and that such a package would need to be handled by power machinery. It is common practice to handle heavy material by power operated lift trucks by stacking the material on pallets. Such a method can be used to handle anodes but it is not satisfactory unless the anodes are crated.

In accordance with the present invention, the crating of the anodes is eliminated and a combined package and skid is formed by the simple

2

expedient of placing a plurality of anodes in parallel relation on a plurality of skid bars and tying the anodes to the skid bars whereby the skid bars themselves become the only crating material necessary other than the securing means for tying the bars thereto, and the parallel anode bars are at the same time held in the form of a firm package by the skids and hold the skids in position to form the equivalent of a pallet. In this way I solve the problem of securing the bars together and at the same time facilitate the handling of the package by a lift truck or the like.

Referring to the drawings, the numeral 10 indicates the anode bars standing on edge as best seen in Fig. 3. Extending at right angles to the anode bars 10 are skids 11 which may take the form of wooden beams of, for example, 4" x 4" cross-section which need not be returned to the shipper. In order to secure the skids 11 to the anode bars 10, I provide ties 12 which may take the form of metal straps, and secure them to the skids 11 by passing them around the anode bars 10 and through the openings 15 in the skids 11. The straps 12 as well as a center strap 13 not associated with any skid bar may be secured in place in any suitable manner as by overlapping and spot-welding as indicated at 14. Other means of securing the ends of the straps together may be employed as will be understood by persons skilled in the packaging art. The top portion of the tie extends along the top of the anode pack in contact with the top edges of the anode bars, a distance approximately equal to the sum of the maximum thicknesses of said bars less the difference between the minimum and maximum thicknesses of one of said bars. The side portion of the ties are continuous with the top portion at each end thereof and extend downwardly along the curved surfaces of the anode bars at the ends of the pack and pass through the openings 15 in the skids 11, and are connected by the bottom portion 12 which is of a length approximating the sum of the maximum thicknesses of the anode bars. In view of the peculiar shape of the anode bars as shown, it is desirable to make use of the center strap 13 to afford a more rigid package.

It is not essential that the straps 12 pass through openings such as those 15, but it is feasible to make the skid bars shorter or even of the same length with respect to the width of the anode pack and pass the straps around the ends thereof securing them by means of a staple 55 or a notched construction at the end of a bar or

relying on friction to hold them in place. In either case the skids 11 may be of a length just sufficient to be coextensive with the load but preferably should be somewhat longer as indicated in Figs. 2 and 3.

Other means of securing the anode bars to the skids 11 may be devised also. For example, a board may be placed over the anode bars and secured to the skids by means of bolts or lag screws; or wires may be passed over the top of the anode bars, across under the skid bars, back across the top of the anode bars and under the other end of the skid bars a plurality of turns and the ends then twisted together. These various securing means have in common the essential feature of securing the anode bars to the transverse skid bars in a secure fashion so that these elliptical cylinders may be arranged as shown in Fig. 3 and may make a firm easily handled package. I find this arrangement more effective than a plurality of layers of these bars lying flat on their sides. A single layer on edge results in a firmer package than the same number in a plurality of layers arranged flatwise. Two layers may be arranged on edge with a separator between such as strips overlying the skids and the ties applied as above described.

While I have not illustrated any protective covering, it may be desirable to wrap the package illustrated with burlap, paper or the like to keep the anode bars clean and avoid introduction of any foreign materials into the electroplating bath.

While I have shown and described the preferred embodiment of my invention, it is obvious that variations may be made, some of which have been indicated above, and I, therefore, desire to be limited only in accordance with the appended claims.

Having thus described my invention, what I claim is:

1. A package comprising a plurality of parallel anode bars of generally elliptical cross-section arranged on edge in a pack one anode thick, each anode bar having a side in contact with the side of an adjacent bar, and a plurality of rigid skids secured to said anode bars on the same side thereof in contact with the edges thereof and extending at approximately right angles thereto, each of said skids having a pair of spaced openings extending therethrough, said skids being secured to said anode bars in the relative position aforesaid by means of ties each passing around said bars transversely thereof through said openings and around a portion of a skid longitudinally thereof, each said tie having a top portion extending across the package adjacent to the edges of said bars remote from said skids and said portion being of a length approximately equal to the sum of the maximum

thicknesses of said bars less the difference between the minimum and maximum thicknesses of one of said bars, side portions continuous with said top portion at each end thereof and passing downwardly adjacent a curved surface of an anode bar and a bottom portion connecting said side portions and being of a length approximating the sum of the maximum thicknesses of said anode bars, and said skids being longer than the sum of the maximum thicknesses of said bars.

2. A package comprising a plurality of parallel anode bars of generally elliptical cross-section arranged on edge in a pack one anode thick, each anode bar having a side in contact with the side of an adjacent bar, and a plurality of rigid skids secured to said anode bars on the same side thereof in contact with the edges thereof and extending at approximately right angles thereto, each of said skids having a pair of spaced openings extending therethrough, said skids being secured to said anode bars in the relative position aforesaid by means of ties each passing around said bars transversely thereof through said openings and around a portion of a skid longitudinally thereof, each said tie having a top portion extending across the package adjacent to the edges of said bars remote from said skids and said portion being of a length approximately equal to the sum of the maximum thicknesses of said bars less the difference between the minimum and maximum thicknesses of one of said bars, side portions continuous with said top portion at each end thereof and passing downwardly adjacent a curved surface of an anode bar and a bottom portion connecting said side portions and being of a length approximating the sum of the maximum thicknesses of said anode bars, said skids being longer than the sum of the maximum thicknesses of said bars, and a tie disposed intermediate said skids and extending around said bars whereby to hold the latter more firmly against displacement with respect to each other.
